UNITED STATES PATENT OFFICE.

ERNEST HOLLOWBECK, OF DAVISON, MICHIGAN.

DESIGN FOR A DOLL'S CRADLE.

Application filed June 1, 1926. Serial No. 17,905. Term of patent 7 years.

To all whom it may concern:

Be it known that I, ERNEST HOLLOWBECK, a citizen of the United States of America, and a resident of Davison, in the county of Genesee and State of Michigan, United States of America, have invented a new, original, and ornamental Design for a Doll's Cradle, of which the following is a specifi-

cation, reference being had to the accompanying drawing, forming part thereof.

The figure represents a perspective view of a doll's cradle embodying my design.

I claim:

The ornamental design for a doll's cradle, as shown.

ERNEST HOLLOWBECK.
